UNITED STATES PATENT OFFICE.

FRANK RUDOLPH NYBERG, OF LAMAR, COLORADO, ASSIGNOR OF ONE-HALF TO GEORGE J. GARVIN, OF LAMAR, COLORADO.

ATTACHMENT FOR AUTOMOBILES.

1,134,759.

Specification of Letters Patent.

Patented Apr. 6, 1915.

Application filed August 11, 1914. Serial No. 856,231.

To all whom it may concern:

Be it known that I, FRANK R. NYBERG, a citizen of the United States, and a resident of Lamar, in the county of Prowers and State of Colorado, have invented a new and useful Improvement in Attachments for Automobiles, of which the following is a specification.

My invention is an improvement in attachments for automobiles, designed to be attached to the wheels, and wherein a housing is provided capable of attachment to and removal from the wheels and carrying a series of dogs arranged in spaced relation and mounted for movement beyond the periphery of the wheel and normally lying within the periphery of the wheel, and wherein other mechanism is provided in connection with the dogs for extending the dogs at predetermined times.

In the drawings:—Figure 1 is a vertical section through a wheel provided with the improved attachment, Fig. 2 is a side view of the attachment from the inner side, Fig. 3 is a similar view from the outer side, Fig. 4 is a perspective view of the connecting ring, Fig. 5 is a section on the line 5—5 of Fig. 1, looking in the direction of the arrows adjacent to the line, and Fig. 6 is an enlarged sectional view of a modified arrangement.

The present embodiment of the invention is shown in connection with a wheel of ordinary construction, comprising a felly 1 supporting a rim 2 for carrying a tire 3, and the felly is connected to the hub (not shown) by means of spokes 4. The attachment comprises a casing or housing adapted to engage one side of the wheel and a holding ring adapted to engage the other side, together with other mechanism for connecting the housing to the ring, and arranged transversely of the wheel.

The housing consists of a disk 5, having a lateral marginal flange 6, and the flange is provided with an inwardly extending web 7 at approximately right angles to the flange 6 and approximately parallel to the disk 5, and the web is provided with a laterally extending rib 8, for engaging the spokes of the wheel. The housing 5—6—7—8 is an integral structure, having a diameter somewhat less than the over-all diameter of the wheel.

The peripheral surface of the flange 7 is

slightly beyond the rim 2 when the attachment is in place, and the rib 8 is designed to fit within the felly 1, with its outer face abutting the inner surface of the felly between the spokes. The edge of the rib remote from the disk 5 is provided with notches or recesses 9 for receiving the spokes 4, and the notches 9 are of such depth that the web 7 will be spaced slightly outward from the adjacent edge of the rim 2.

The disk 5 is slightly concavo-convex, the convex surface being remote from the wheel, and the said disk is provided with an annular series of openings 10 coaxial with the wheel, for the sake of lightness and to permit access to the interior thereof. A disk 11 is arranged at the center of the disk 5, and in spaced relation and parallel therewith, and the disk 11 is connected to the disk 10, by connecting bars 12, the said bars in the present instance being integral with both disks.

The inner face of the disk 5 is provided with an annular series of pairs of laterally spaced lugs 13, each pair of lugs being between a pair of bars 12. One end of a lever 14 is received between each pair of lugs, and pivoted thereto as indicated at 15, and the levers extend laterally from the disk 5 inwardly beyond the disk 11, and the free end of each lever is provided with a weight 16, in the form of a ball in the present instance.

The disk 11 limits the inward movement of the balls, and each lever and the ball connected therewith is normally pressed toward the disk by means of a coil spring 17. Each of the springs is connected at one end to an opening 18 in the lever 14 adjacent to the ball, and at the other end to the eye of an eye bolt 19. Each of the eye bolts is passed through a lug 20, extending laterally from the disk 11, and is engaged by a nut 21 on the inner face of the lug. By means of the nuts 21 the tension of the springs 17 may be varied.

Holding dogs 22 are mounted to slide radially of the housing 5—6—7—8, and the flange 6 of the housing is provided with an opening 23 for the outer end of each dog. Each of the dogs 22 is X or cross shape in cross section, and the openings 23 for the dogs are similarly shaped. That portion of each dog perpendicular to the plane of the wheel is enlarged at its outer end to form a head 24, and the head is too large

to pass inwardly through the opening 23 from the dogs.

The inner end of each of the dogs is reduced as shown at 25, and the reduced portion is longitudinally slotted as shown at 26, and a yoke-shaped clip 27 engages each slot to connect the dogs to the adjacent lever 14. The body of each clip extends through the slot 26, and the arms of the clip engage opposite faces of the lever, and are pivoted thereto as indicated at 28.

A coil spring 29 encircles the reduced portion of each dog between the body thereof and a stop or washer 30, encircling the reduced portion, and each spring normally acts to force the clip 27 inwardly, that is, to retain the clip at the inner end of the slot 26. The inward movement of the washer 30 is limited by its engagement with the body of the adjacent clip 27.

The dogs are guided in their radial movement by pairs of lugs 31. The lugs are struck up from the inner edge of a ring 32, arranged between the disk 11 and the flange 6 of the housing, and the ring is held in fixed position by means of plates 33. The plates 33 are rigidly connected at their inner ends to the ring 32, and the outer end of each plate is offset inwardly toward the wheel, and rigidly connected to the web 7. Thus the ring is supported in spaced relation with respect to the web 7 and with respect to the disk 11.

The outer end of each of the portions of each dog is beveled in opposite directions to form a point for permitting the dog to easily enter the surface of the road over which the car is passing, and the outer edge of the ring 32 is beaded as shown at 34 around a reinforcing wire or rod 34^a.

The attachment is secured to the wheel by means of the ring shown more particularly in Fig. 4, and bolts which are connected with the plates 33 before mentioned. The ring 35 35^a is arranged on the opposite side of the wheel from the housing with one face thereof abutting the adjacent side of the felly 1. The ring is of such external diameter that the periphery thereof will be just within the rim 2 and the inner edge thereof is provided with bayonet slots 36.

The bolts 37 are pivoted to the plates 33 by means of U-shaped clips 38. The body of each of the clips engages the eye of the bolt, and the arms are passed through openings in the adjacent plate 33, and are engaged by nuts 39 on the opposite face of the plate. The free ends of the bolts are engaged with the bayonet slots 36 of the ring 35, and wing nuts 40 are threaded on to the bolts to hold the parts in place.

In use, the attachment is arranged as shown in Fig. 1, the rib 8 fitting within the felly 1, and with the spokes 4 received in

the notches 9. The wing nuts 40 are loosened on the eye bolts 37, and the said bolts are engaged with the bayonet slots 36. The nuts 40 are then tightened and the attachment is firmly connected to the wheel. The ring 35 is sectional in order that it may be placed without requiring the removal of the wheels from the axle. This ring is on the inner side of the wheel, and it is obvious that were the ring a continuous ring the wheel would necessarily be removed from the axle before the ring could be placed.

The ring consists of sections 35 and 35^a. A plate 41 is rigidly connected at one end to the section 35^a as indicated at 42, and is so pivotally connected to the section 35 as indicated at 42. At the opposite end the section 35 has a U-shaped clip 44, secured thereto, and a latch plate 45 is connected to the section 35^a at the said end.

The sections are separated to permit the ring to be placed on the wheel by pulling the latch plate 45 out of the clip or socket 44. After the ring has been placed around the axle the plate 45 is pushed into the socket, the eye bolts are engaged with the bayonet slots and the nuts 40 are tightened.

In operation, when the wheel is in place, under ordinary conditions the dogs will not extend beyond the tread of the tire, that is, beyond the periphery of the wheel considered as a whole. The springs 17 are adjusted to hold the dogs within the periphery of the wheel until the wheel exceeds a predetermined speed. In this manner whenever the speed for which the springs are set is exceeded the dogs will be thrown outward by centrifugal force acting on the weights 16. This force will be sufficient to overcome the tension of the springs 17, and as the levers move outward they will move the dogs outward.

Should a dog meet with an obstruction in the road as for instance a stone or the like the spring 29 may yield to prevent injury to the dogs. It will be obvious that the device may be adjusted to cause the dogs to extend at any particular rate of speed. The dogs are limited in their outward movement by stops 46. These stops may be of any desired character, and are connected to the dogs in a position such that they will engage the inner surface of the flange 6 when the dogs are sufficiently extended.

The inward movement of the dogs is limited by the engagement of the head 24 with the inner end of that portion of the opening 23 which is in the disk 5. It will be obvious from the description that the improvement may be easily attached to a wheel or taken off from the same, and that when in place, the springs may be adjusted to cause the dogs to be extended whenever the speed of the vehicle attains a predetermined point.

In Fig. 6 is shown a modified arrangement for simultaneously tensioning the springs that hold the balls from outward movement. In this construction the disk 5 11^a corresponding to the disk 11 has the lugs 20, through which are passed the eye bolts 50, to which the springs 17^a connected with the levers 14^a, are connected, one end of each spring being connected to the lever and 10 the other to the eye bolt.

The levers have the balls 16^a corresponding to the balls 16, and each eye bolt is provided with a nut 51 on the opposite side of the lug from the lever, the nut being in the 15 form of a bevel pinion. It will be understood that each of the six eye bolts of the levers has a bevel pinion for the nut. All of the pinions are engaged by a bevel gear wheel 52, which is detachably connected 20 with a stem 53, journaled in the disk 11^a. A circular head 54 is secured to one end of the stem and the head fits against the inner face of the bevel gear wheel and is secured thereto by means of bolts and nuts 55. The 25 stem 53 passes through a collar 56 and then through the disk, and on the opposite side of the disk from the gear wheel the stem is square as indicated at 57 to fit a square opening in the thumb nut 58. Beyond the 30 square portion the stem is reduced and threaded as indicated at 59, and is engaged by a nut 60 to hold the thumb screw in place on the square portion.

In operation, when it is desired to vary 35 the tension of the spring 17^a, it is only necessary to turn the stem 53 by means of the thumb screw. Since the bevel gear 52 engages all of the nuts 51, the nuts of the six bolts will be simultaneously turned in the 40 same direction to increase or decrease the tension of the springs 17^a.

I claim:

1. An attachment of the character specified, comprising a substantially cylindrical housing, dogs mounted for radial movement in the housing, said housing having openings in its periphery to permit the dogs to be extended, means for limiting the movement of the dogs in both directions, levers 45 pivoted to the housing and extending inwardly, a lever being provided for each dog and the levers being arranged in annular series concentric with the housing, each lever having its outer end weighted, a lost motion connection between each lever and the adjacent dog, a spring arranged between the dog and the lever and normally holding the lever at the inner end of the connection, said housing having means for limiting the inward swinging movement of the levers, a spring normally pressing each lever inward, means for varying the tension of each of the last-named springs, and means for connecting the housing to a wheel, said means comprising a laterally extending annular rib on 50
2. An attachment of the character specified, comprising a rib 70 having a section 75 adapted to fit the rim of the wheel and having notches at the edge remote from the housing for receiving the spokes, a sectional ring adapted to fit the opposite face of the wheel from the housing, the sections being detachable to permit the ring to be placed over the axle, means for connecting the sections, and eye bolts pivoted to the housing and adapted to extend transversely of the wheel between the spokes, the ring having its inner edge provided with bayonet slots for receiving the eye bolts, and nuts threaded on to the bolts.
3. An attachment of the character specified, comprising a substantially cylindrical housing, dogs mounted for radial movement in the housing, said housing having openings in its periphery to permit the dogs to be extended, means for limiting the movement of the dogs in both directions, levers pivoted to the housing and extending inwardly, a lever being provided for each dog and the levers being arranged in annular series concentric with the housing, each lever having its outer end weighted, a lost motion connection between each lever and the adjacent dog, a spring arranged between the dog and the lever and normally holding the lever at the inner end of the connection, said housing having means for limiting the inward swinging movement of the levers, a spring normally pressing each lever inward, means for varying the tension of each of the last-named springs, and means for connecting the housing to a wheel.
4. An attachment of the character specified, comprising a housing of approximately cylindrical form, dogs movable radially of 80 the housing, said housing having openings in its peripheral surface for permitting the ends of the dogs to be extended beyond the housing, means for limiting the movement of the dogs in both directions, a lever for 85 each dog, said levers being arranged in an annular series concentric with the housing, each lever being pivoted to the housing and having a weight at its free end, resilient means normally pressing each lever inwardly, means for varying the tension of each of the said means, a connection between each lever and the adjacent dog for moving the said dog when the lever is moved, means for limiting the inward movement of the 90 levers, and means for detachably connecting the housing to a wheel, the connection between each lever and the adjacent dog being a lost motion connection, and a spring arranged between the dog and the lever for 95 permitting the dog to move inwardly with respect to the lever but normally holding the dog in outward position.
5. An attachment of the character specified, comprising a housing of approximately 100
6. An attachment of the character specified, comprising a housing of approximately 105
7. An attachment of the character specified, comprising a housing of approximately 110
8. An attachment of the character specified, comprising a housing of approximately 115
9. An attachment of the character specified, comprising a housing of approximately 120
10. An attachment of the character specified, comprising a housing of approximately 125
11. An attachment of the character specified, comprising a housing of approximately 130

4

cylindrical form, dogs movable radially of the housing, said housing having openings in its peripheral surface for permitting the ends of the dogs to be extended beyond the 5 housing, means for limiting the movement of the dogs in both directions, a lever for each dog, said levers being arranged in an annular series concentric with the housing, each lever being pivoted to the housing and 10 having a weight at its free end, resilient means normally pressing each lever inwardly, means for varying the tension of each of the said means, a connection between each lever and the adjacent dog for moving 15 the said dog when the lever is moved, means for limiting the inward movement of the levers, and means for detachably connecting the housing to a wheel.

5. An attachment of the character specified, comprising a housing of approximately 20 cylindrical form, dogs movable radially of the housing, said housing having openings in its peripheral surface for permitting the ends of the dogs to be extended beyond the 25 housing, a lever for each dog, said levers being arranged in an annular series concentric with the housing, each lever being pivoted to the housing, and having a weight at its free end, resilient means normally 30 pressing each lever inwardly, means for varying the tension of each of the said means, a connection between each lever and the adjacent dog for moving the said dog when the lever is moved, means for limiting 35 the inward movement of the levers, and means for detachably connecting the housing to a wheel.

6. An attachment of the character specified, comprising a housing of approximately 40 cylindrical form adapted to be secured to a vehicle wheel, dogs movable radially of the housing to a position within the periphery of the wheel or beyond said periphery, the housing having openings in its periphery 45 for permitting the extension of the dogs, a weighted lever pivoted to the housing at the inner end of each lever and adapted to be swung outwardly by centrifugal force, and a connection between each lever and the adjacent dog, said connection being a lost motion 50 connection, and yielding mechanism for normally holding the dog in outward position with respect to the lever, and means for detachably connecting the housing with 55 the wheel.

7. An attachment of the character specified, comprising a housing of approximately cylindrical form adapted to be secured to a vehicle wheel, dogs movable radially of the

housing to a position within the periphery 60 of the wheel or beyond said periphery, the housing having openings in its periphery for permitting the extension of the dogs, a weighted lever pivoted to the housing at the inner end of each lever and adapted to be 65 swung outwardly by centrifugal force, and a connection between each lever and the adjacent dog, said connection being a lost motion connection, and yielding mechanism 70 for normally holding the dog in outward position with respect to the lever.

8. An attachment of the character specified, comprising a housing of approximately cylindrical form adapted to be secured to a vehicle wheel, dogs movable radially of the 75 housing to a position within the periphery of the wheel or beyond said periphery, the housing having openings in its periphery for permitting the extension of the dogs, a weighted lever pivoted to the housing at 80 the inner end of each lever and adapted to be swung outwardly by centrifugal force, and a connection between each lever and the adjacent dog.

9. An attachment of the character specified, comprising a housing of approximately 85 cylindrical form adapted to be secured to a vehicle wheel, dogs movable radially of the housing to a position within the periphery of the wheel or beyond said periphery, 90 the housing having openings in its periphery for permitting the extension of the dogs, mechanism connected with each dog and with the housing for moving the dog, said mechanism being operated by centrifugal 95 force, and resilient mechanism for pressing each dog inwardly, each of said mechanisms being adjustable.

10. An attachment of the character specified, comprising a housing of approximately 100 cylindrical form adapted to be secured to a vehicle wheel, dogs movable radially of the housing to a position within the periphery of the wheel or beyond said periphery, 105 the housing having openings in its periphery for permitting the extension of the dogs, mechanism connected with each dog and with the housing for moving the dogs, said mechanism being operated by centrifugal force, resilient mechanism for pressing each dog inwardly, each of the said mechanisms being adjustable, and a common means engaging all of the said mechanisms for simultaneously adjusting the same.
